UNITED STATES PATENT OFFICE

2,442,309

OVERHEAD DOOR CONSTRUCTION

William A. Norberg, Quincy, Ill., assignor to
Raynor Manufacturing Company, Dixon, Ill., a
corporation of Illinois

Application January 31, 1946, Serial No. 644,617

4 Claims. (Cl. 16—94)

1

This invention relates to overhead door construction and the like. The invention will be obviously applicable to other similar uses.

In the use of overhead door structures and the like wherein a flexible lifting element is employed in conjunction with a counterbalance, etc., to facilitate the raising of the door, considerable difficulty has been experienced with the wear and breakage of the flexible element, particularly near its point of connection with the lower portion of the door. The irregular and heavy strains thrown upon the cable or other flexible element at this point of junction, and particularly where it approaches a sheave or rotary guide member, are extremely hard upon the metal structure of the element because it is usually bent or in an angular position at the time such strains are imposed. The result has been a fraying or breaking of the cable or other element and the rendering of the door construction out of order for the period required for repair or substitution of a new cable.

An object of the invention is to overcome the above disadvantages and to provide a structure in which the cable is not subjected to the bent or angular positions described during the lifting operations. A further object is to provide a structure wherein the cable connections are pivotally carried by a saddle mounted upon the door for turning movement with the flexible element so as to relieve the flexible element of distortion or bending movement during the door elevating or descending operations. A further object is to provide a bracket and flexible element connecting structure wherein the roller shaft is employed for mounting a saddle to which the flexible element is secured and which saddle provides a rotatable structure which will permit lifting of the door while at the same time adjusting itself so as to remain in alignment with the lifting element when the door bottom swings away from vertical alignment with such element. Other specific objects and advantages will appear as the specification proceeds.

The invention is illustrated, in a preferred embodiment, by the accompanying drawing, in which—

Figure 1 is a perspective view of the bracket and connecting structure embodying my invention, the structure being shown separated from the door; Fig. 2, a perspective view of the saddle member carried by the shaft of the bracket; Fig. 3, a broken side view of the door structure and track and lifting mechanism associated therewith, part of the track being broken away to show the improved connecting means; Fig. 4, a view similar

2

to Fig. 3 but showing the connecting structure at the top of its movement where the door has moved substantially to a horizontal position; Fig. 5, a rear view in elevation of the bracket and roller structure; and Fig. 6, a plan sectional view, the section being taken as indicated at line 6—6 of Fig. 5.

In the illustration given, A designates a door; B, a track structure therefor; C, lifting mechanism; and D, the bracket and connecting structure employed for joining the flexible lifting member to the door.

The door A may be of any suitable construction. It may consist of a single panel or a multiple of panels. In the illustration given, at least three panels are shown, the panels being separated at the points indicated by the numeral 10, and the panels being connected by the usual hinges 11 carrying a roller 12 upon the hinge pin. It will be understood that any type of hinge- or roller-carrying structure may be employed. If desired, a guide roller 13 may be supported at the upper end of the top panel.

The track structure B may be of any suitable type or construction. In the illustration given, it comprises a metal track member 14 secured to the side wall of the building in which the door is mounted. Such structure is well known. Two tracks are employed along marginal portions of the entrance to a building, and the door has rollers at its sides engaged in such tracks. By means of the curved track, the door moves first in a vertical direction and then is directed finally to a generally horizontal position along the top of the room or compartment.

The lifting element C may be of any suitable construction. It may be formed of chain, cable, or any other suitable material. In the illustration given, the element is in the form of a cable which passes over the rotary member or sheave 15 and is guided thereby. The inner end of the cable is connected to the usual counterbalancing mechanism (not shown).

The structure D herein consists of a bracket member for engaging a lower bottom corner of the door, a shaft mounted therein, and a saddle carried by the shaft and provided with an extension to which the flexible element C is connected. The bracket 16, in the illustration given, consists of a flat web portion, with holes through which fastening means may be extended for connecting it to the door. The bottom portion of the bracket on its front side is provided with forwardly-turned flanges 17 and 18 adapted to engage the corner edges of the door bottom. Spaced

portions of the bracket member 16 are struck out and turned rearwardly to provide ears 19 which are perforated to receive the shaft 20. The inner end of shaft 20 may be flattened to provide a retaining collar or edge 21. A roller 22, preferably mounted upon ball bearings, is carried by the end of shaft 20.

The saddle structure 23 herein employed has a connecting means for the flexible element C and is preferably formed with side flanges 24 having aligned openings 25 therein adapted to receive the shaft 20. The flanges 24 are integrally connected by a bottom wall or web 26. One of the side flanges 24 is projected forwardly to provide an extension 27, as shown more clearly in Figs. 2 and 6, and a pin 28 is carried by the extension. In the illustration given, a collar 29 is fixed to the pin 28 or formed integrally therewith. The end of the pin 28 is provided with an opening 30 through which a cotter pin 31 or other retaining means may be passed.

Any suitable means for retaining the cable C upon the pin 28 may be employed. In the illustration given, I provide a metal strip 32 perforated at its lower end to receive the pin 28 and also perforated near its top to receive a clamping screw 33. Opposite the metal piece 32 is a clamping member 34, which is likewise perforated at its lower end to receive the pin 28 and also near its top to receive the clamping screw 33. The cable C extends downwardly around the clamping screw 33 and is doubled back, as shown more clearly in Fig. 1, with the upper end of the clamping member 34 extending with a U-shaped curve about the cable. The clamping screw 33 preferably has its inner end threaded to engage a nut or the like, and rotation of the screw 33 by means of a screw driver clamps the member 34 tightly about the looped cable end. At the same time, the members 33 and 32 are free to swing upon the pivot pin 28.

Operation

In the operation of the structure, when the door is in its lowered or closed position, as illustrated in Fig. 3, the lifting element C is tensioned under the force of the counterbalancing mechanism and draws the extension 27 of the saddle member in a vertical direction. This movement causes the saddle 23 to swing upon the pivot pin 28 and the forward end of the web portion 26 of the saddle engages the bracket 16. Lifting force therefore upon the element C tends to draw the door upwardly because the saddle member can swing no farther in its movement toward the bracket. This relation continues while the lower portion of the door is vertically aligned or in parallel with the lifting element C.

When, however, the door, and particularly the bottom panel thereof, begins to leave its true vertical path and to diverge from a line parallel with the lifting element C, the saddle member tends to swing more and more upon pivot 20 so as to remain in alignment with the flexible lifting element C, as illustrated more clearly in Fig. 4. Thus, there is avoided any angular or bent positioning of the element C by reason of its connection to the door and, instead, as shown in Fig. 4, the saddle member and the flexible element, with the connections therebetween, lie in a straight line.

As the lower portion or lower panel of door A swings away from its parallel position with the lifting element C, the saddle 23 and the pivot means for connecting it with element C pass

through a series of angular positions with respect to the door A but, with respect to the element C, the saddle member swings as nearly as possible into a true line with the element, reaching as it

5 approaches the roller 15 the straight line arrangement illustrated in Fig. 4 but over a relatively long reach of the track. Thus, in the critical range where the door and lifting element C assume different and almost opposite directions, 10 the connecting means described is highly effective in relieving the element C of any bending or twisting strains and protects it from fraying or breaking. Further, the operation is accomplished with less noise and there is less frictional 15 resistance to the smooth operation of the door movement.

The improved connecting means occupies very little space and utilizes the shaft already necessary for the supporting of the roller 22. Free 20 pivotal movement of the saddle is provided in one direction, namely when the guide member C and door follow diverging paths, while at the same time movement in an opposite direction is prevented by the bringing of the web portion 26 25 against the bracket or any portion thereof so as to assist in the lifting of the door through the force exerted by the lifting element C.

The bracket structure is easy to apply and forms substantially a reinforced corner for the 30 door bottom, while at the same time affording integral supports for the shaft with its roller and saddle members. The cable may be readily attached or detached to the clamping members 32 and 34 which pivot upon the pin 28.

35 While in the foregoing specification, I have set forth a large number of details as illustrative of one mode of employing the invention, it will be understood that such details may be varied widely by those skilled in the art without departing 40 from the spirit of my invention.

I claim:

1. A connecting structure for use with an overhead door shiftable in marginal tracks for generally vertical and horizontal movements and 45 with which a lifting cable and a rotary element for guiding the lifting element in its movements are employed, said connecting structure comprising a bracket secured to a bottom side portion of the door and provided with integral rearwardly-extending members, a shaft rotatably mounted in said members, a saddle member rotatably mounted on said shaft and provided with a forwardly-projected extension, and means for securing said cable to said extension.

50 2. A connecting structure for use with an overhead door shiftable in marginal tracks for generally vertical and horizontal movements and with which a lifting cable and a rotary element for guiding the lifting element in its movements are employed, said connecting structure comprising a bracket secured to a bottom side portion of the door and provided with integral rearwardly-extending members, a shaft rotatably mounted in said members, a saddle member rotatably 55 mounted on said shaft and provided with a forwardly-projected extension, and pivotally-mounted means carried by said extension for securing said cable thereto.

3. A connecting structure for use with an overhead door shiftable in marginal tracks for generally vertical and horizontal movements and with which a lifting cable and a rotary element for guiding the lifting element in its movements are employed, said connecting structure comprising a bracket secured to a bottom side portion of

the door and provided with integral rearwardly-extending members, a shaft rotatably mounted in said members, a saddle member rotatably mounted on said shaft and provided with a forwardly-projected extension, said saddle member having a side flange projected to provide a lateral extension, a pin carried by said extension, and means for connecting said cable to said pin and in rotatable relation therewith.

4. A connecting structure for use with an overhead door shiftable in marginal tracks for generally vertical and horizontal movements and with which a lifting cable and a rotary element for guiding the lifting cable in its movements are employed, said connecting structure comprising a bracket secured to a bottom side portion of the door and provided with rearwardly-extending members, a shaft rotatably mounted in said

members, a saddle member rotatably mounted on said shaft and provided with a forwardly-projected extension adapted to engage said bracket when the saddle is swung toward said bracket, said saddle having a side flange extended to provide a lateral extension, and pivotally-mounted means carried by said lateral extension for securing said cable thereto.
